UNITED STATES PATENT OFFICE

107,535

DESIGN FOR A MOUTHPIPE KEY FOR A SAXOPHONE

Hugh W. Loney, Elkhart, Ind., assignor to C. G. Conn, Ltd., Elkhart, Ind., a corporation of Indiana

Application September 27, 1937, Serial No. 71,805

Term of patent 14 years

To all whom it may concern:

Be it known that I, Hugh W. Loney, a citizen of the United States residing at Elkhart, Elkhart County, Indiana, have invented a new, original, and ornamental Design for Mouthpipe Keys for Saxophones, of which the following is a specification, reference being had to the accompanying drawing, forming a part thereof.

Figures 1 and 2 are perspective views of the mouthpipe key for a saxophone, showing my new design.

I claim:

The ornamental design for a mouthpipe key for a saxophone, as shown.

HUGH W. LONEY.
